UNITED STATES PATENT OFFICE

2,419,871

INNERSOLE AND METHOD OF MAKING
THE SAMEFred L. Ayers, Waltham, Mass., assignor of
twenty-two one-hundredths to Charles G.
Keferstein, New York, N.Y.

Application January 8, 1945, Serial No. 571,739

5 Claims. (Cl. 36—22)

1

This invention relates to innersoles of that type wherein the inseam receiving rib includes a lip formed by inwardly channeling about the edge of at least the forepart of an innersole blank, the lip being turned inwardly and reinforced by one or more layers or strips cemented in position, an inner layer or strip being folded back on itself. It is highly desirable in such constructions that the rib be inclined sharply inwardly at least during the placing of the inseam fasteners.

It is an object of the present invention to provide a construction and method of making by which this sharp inward inclination of the rib is assured. This is done in accordance with this invention by employing for the inner reinforcing strip a strip coated on one face with a cement for securing it to the top face of the blank and to so fold the strip that a portion of the coated face secures the strip in the desired position, this strip holding the lip in position.

For a more complete understanding of this invention, reference may be had to the accompanying drawings, in which

Figure 1 is a perspective view of an innersole constructed in accordance with and embodying the invention.

Figure 2 is a detail sectional view on line 2—2 of Figure 1.

Figure 3 is a perspective view showing the folding of a cement coated strip and its application to a channeled sole blank and the folding back of the channel lip against the strip.

Figures 4, 5 and 6 are detail sectional views on correspondingly numbered section lines of Figure 3.

Referring to the drawings, at 1 is shown an innersole blank having a marginal inwardly directed channel cut around at least the forepart and preferably as shown extending also through the shank of the blank though, if desired, it might also be extended around the heel. This channeling operation forms a lip 2 on one face and a feather 3 beneath the lip. There is then applied to the lip face of the blank and substantially coextensive in length therewith, a reinforcing strip of sheet material 4. As shown best in Figures 2, 5 and 6, this strip 4 is preferably folded on itself longitudinally at 5 to form a double layer comprising an inwardly turned portion 6 overlying a portion 7 which extends preferably inwardly of the portion 6 where it forms a single layer 8 which is cemented to the lip face of the blank 1. This folding or convoluting of the strip 4 may be accomplished as it

2

is being fed to the face of the blank as shown in Figure 3 where the strip is shown as passing through the folder F. Preferably the strip is convoluted so that a marginal portion 9 of the upper layer 6 is turned inwardly between the layers 6 and 7. Commonly this strip material is coated on one face with a suitable adhesive, this face being the outer face of the convoluted portion so that it is on the side confronting the face of the blank. This also brings the cement coated face of the portion 9 against the uncoated upper face of the portion 8 so that when the parts are pressed together the inner edge portion of the outer convolution 6 is cemented to the single layer portion 8. This cement attachment holds the stitching rib in inwardly inclined position during the placing of inseam stitches, after which it is not important that this inward inclination be retained, since the remaining portion 20 of the innersole lip formed by the portions 6 and 9 is removed by the inseaming trimming operation.

The strip is cemented to the blank with its outer folded edge portion 5 adjacent to the root of the lip 2 so that this lip may be turned inwardly thereover and secured to the reinforcing strip at least partly by the cement coating of this strip as shown in Figure 6. Preferably the inseam-receiving rib is further reinforced by a flat strip 10 which is cemented to the outer face of the inwardly turned lip 2 and against the channel face 11 of the marginal feather 3, as shown best in Figure 2. The stitch-receiving rib then comprises a portion of the reinforcing strip 10, the lip 2, and the upper layer 6 with its inwardly turned marginal convolution 9 of the inner strip 4.

This application is a continuation-in-part of my application, Serial No. 531,758, filed April 19, 1944, for Innersole and method of making the same.

From the foregoing description of an embodiment of this invention, it will be evident to those skilled in the art that various changes and modifications might be made without departing from its spirit or scope.

I claim:

1. The method of making an innersole, which comprises folding a strip of sheet material adhesively coated on one face lengthwise on itself in a pair of convolutions and with the coated face outwardly to thus bring an in-turned edge face of said strip with its coated face against the uncoated face of the outer convolution which extends therebeyond, cementing said folded strip

with said outer convolution inwardly facing, to one face of an innersole blank inwardly from its edge, said blank having a marginal channel defining a lip on the face to which said strip is cemented, and folding said lip inwardly and cementing it to the outer face of the convoluted portion of said strip.

2. The method of making an innersole, which comprises folding a strip of sheet material adhesively coated on one face lengthwise on itself in a pair of convolutions and with the coated face outwardly to thus bring an in-turned edge face of said strip with its coated face against the uncoated face of the outer convolution which extends therebeyond, cementing said folded strip with said outer convolution inwardly facing, to one face of an innersole blank inwardly from its edge, said blank having a marginal channel defining a lip on the face to which said strip is cemented, folding said lip inwardly and cementing it to the outer face of the convoluted portion of said strip, and cementing a strip of sheet material to the outer face of said lip and against the marginal feather outwardly of said lip.

3. The method of making an innersole, which comprises folding a strip of sheet material lengthwise to form a pair of layers and with the margin of one layer of said material turned inwardly between said layers and cemented to the other of said layers, cementing said folded strip to one face of an inner sole blank with the fold line between said layers facing the edge of said blank, and turning inwardly and cementing the marginal lip of said blank formed by an inwardly directed marginal channel about said blank to the outer face of said one layer.

4. The method of making an innersole, which comprises folding a strip of sheet material lengthwise to form a pair of layers and with the margin of one layer of said material turned inwardly between said layers and cemented to the other of said layers, cementing said folded strip to one face of an innersole blank with the fold line between said layers facing the edge of said blank, turning inwardly and cementing the marginal lip of said blank formed by an inwardly directed marginal channel about said blank to the outer face of said one layer, and cementing a flat strip of sheet material to the outer face of said lip and to the adjacent face of the marginal feather of the innersole outwardly of said lip.

5. An innersole comprising a blank channeled inwardly about its margin to form a marginal lip and a feather, said lip being turned inwardly and cemented to a double portion of a convoluted strip of sheet material, the inner convolution of said material being cemented to an outer convolution thereof, and a layer of strip material cemented to the outer face of said lip and to the channel face of said feather.
